UNITED STATES PATENT OFFICE.

WALTER SCOTT SHIPE, OF BROOKLYN, NEW YORK.

SAFETY EMERY OR CORUNDUM WHEEL.

SPECIFICATION forming part of Letters Patent No. 508,773, dated November 14, 1893.

Application filed December 23, 1892. Serial No. 456,141. (No model.)

To all whom it may concern:

Be it known that I, WALTER SCOTT SHIPE, a citizen of the United States, residing at No. 18 Jefferson street, in the city of Brooklyn, county of Kings, and State of New York, have invented certain new and useful Improvements in Safety Emery or Corundum Wheels; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to emery or corundum wheels for grinding and particularly to that class of wheels having a cup shape, and adapted to end grinding.

The object of my invention is to provide an improved and effective means for making and strengthening emery or corundum wheels.

In carrying out my invention, I provide a disk or face-plate containing anchoring recesses and holes to retain emery or corundum composition which is molded to the form of a hollow cylinder; and the outer edge of which cylinder is protected by sectional rings of metal, such protection permitting revolution at a very high rate of speed without danger of bursting from centrifugal force.

I will first describe my improved emery or corundum wheel with reference to the accompanying drawings, and then define the matter constituting my invention in the claims.

In the accompanying drawings, Figure 1 represents a vertical section of the wheel and arbor, as made upon the line $x-y$ of Figs. 2 and 3. Fig. 2 represents the rear elevation or end view. Fig. 3 represents the front elevation or end view.

In the different figures the same letters refer always to the same parts.

A represents the metal disk or face-plate, which turns or revolves with the common arbor C to which it is bound or clamped by a conical collar D, and binding screw-nut E. The disk or face-plate A is provided in its center with a conical hole the sides of which are at an angle of about sixty degrees with the face of the plate, and has upon the surface in which the said hole is largest a recess

F flaring or widening in its interior; such flaring or widening being preferably curved instead of angular. At certain distances around this recess, holes G are continued through the disk or face-plate A and are countersunk from the opposite side. The object of the continuous recess F and the countersunk holes G, is to contain the emery or corundum grinding composition of which the grinding wheel B is composed, thereby anchoring the said wheel B firmly to the disk or face-plate A; and furthermore, the countersunk holes G afford means by which the wheel B when worn out may be forced off the disk or face-plate A by means of punches directed through the said holes G.

The emery or corundum wheel B is cast in its cylindrical form on and in the disk or face-plate A and within the sectional strengthening bands or rings are seen in section in Fig. 1, each presenting the form of a rhomb or rhomboid, the outer and inner surfaces being independently inclined toward the axis of the wheel; the advantage of which latter form is two-fold, both anchoring the rings in the composition emery wheel B, and affording a shoulder by which the outside ring may be driven off when the composition emery wheel B is worn down to it, which stripping off affords a new grinding space.

The conical collar D is made of such shape as to fit snugly the conical hole before mentioned as being in the disk or face-plate A, and contains a hole fitting closely the arbor C, and is firmly pressed into the conical hole of the said disk or face-plate A by means of screw-nut E, thus binding the device to the arbor firmly, and centering it correctly, and retaining such center.

When the emery or corundum grinding wheel has become worn-out and useless, as before mentioned, the remnants may be forced from the disk or face-plate by means of punches through the countersunk holes G; then placing the rings i, i, i, &c., upon the disk or face-plate, a new emery or corundum composition wheel may be cast therein, thus providing a new and perfect wheel.

Having thus described my invention, what I claim, and desire to secure by Letters Patent, is—

1. In a safety emery or corundum wheel,

sectional reinforcing or strengthening bands or rings; such rings, when placed side by side, presenting serrated surfaces, substantially as and for the purposes described.

5 2. In safety emery or corundum wheels, a metallic disk or face-plate through which are pierced a series of holes that are countersunk from the side of said plate opposite to its face, in combination with the composition emery wheel cast upon the face of said plate, substantially as described.

3. In a safety emery or corundum wheel, the combination of a disk or face-plate having upon its face a continuous annular recess and a series of countersunk holes, a grinding wheel or cylinder composed of emery or other grinding material and cast upon the said disk

or face-plate in such manner that the composition entering the said recess and series of countersunk holes acts as an anchor for the 20 grinding wheel, and metallic rings surrounding the emery or grinding material, substantially as and for the purpose described.

4. In a safety emery or corundum wheel, sectional reinforcing or strengthening bands 25 or rings, such rings when placed side by side presenting a serrated surface, substantially as and for the purpose described.

In testimony whereof I affix my signature in presence of two witnesses.

WALTER SCOTT SHIPE.
